RAILWAY AXLE JOURNAL LUBRICATOR

James J. Hennessy, Chambersburg, Pa., assignor to Hennessy Lubricator Company, Inc., Chambersburg, Pa., a corporation of Delaware

Application March 13, 1950, Serial No. 149,415

17 Claims. (Cl. 308—84)

1

The invention relates to the lubrication of railway axle journals and more particularly to a type of lubricator in which the play of the journal axially crosswise of the track in the box actuates a pump to supply oil from the bottom of the box to the journal.

In an application filed by the present applicant December 7, 1949, Serial No. 131,579, there is disclosed a lubricator characterized by having a collapsible pump body positioned between a lubricant distributor applied to the journal and the actuating arm of a pump operating lever which has an actuated arm disposed to engage and extend outwardly beyond the lower periphery of the collar on the end of the journal.

One object of the present invention is to adapt a lubricator of the type described, including the pump and the actuating mechanism, to be positioned substantially entirely inwardly from the outer end of the journal.

Another object is to facilitate the passage of such a lubricator through the restricted space between the end of the journal and the adjacent portion of the walls of a box mounted on the journal.

The present invention embodies a collapsible pump body supported by the substantially horizontal actuating arm of a bell crank lever, the actuated arm or arms of which extend up abreast of the journal and engage the inwardly facing surface of the usual radial collar on the end of a journal, and preferably the lever arms are jointed intermediate their ends to swing longitudinally of the journal axis towards a folded position to facilitate passage of the pump through the space between the end of the journal and the adjacent portion of the box mounted thereon. Preferably the actuated arms are also pivoted to swing transversely of the journal axis to accommodate their by-passing the journal collar to move into or out of position behind the collar.

This general structure is embodied in the arrangements shown in the accompanying drawings, in which:

Figure 1 is a longitudinal section through an American Association of Railroads ordinary journal box mounted upon an axle journal and having a lubricator of the class described associated therewith.

Figure 2 is in part a transverse vertical section taken on the line 2—2 of Figure 1 and in part upon the line 2a—2a of Figure 1.

Figure 3 is a top view of a pump operating mechanism shown in Figures 1 and 2.

Figure 4 is a side view of the operating mecha-

nism, pump body and distributor with the parts angled about each other from their normal operating position to facilitate their passage through the space between the end of the journal and the adjacent portions of the box walls.

Figures 5 and 6 correspond to the lower portions of Figures 1 and 2 but illustrate another form of the invention.

In the arrangement shown in Figures 1—4, the journal 1 mounts the usual bearing 2 and wedge 3 supporting the box 4 having a bottom wall 5 which curves upwardly transversely of the box to merge with side walls 6 and merges with an upwardly and forwardly extending front wall 7. The lubricator comprises a distributor, including a pad P applied to the face of the journal and supported by springs 8 seated on the box bottom wall, a pump 9 having a collapsible body, and a pump actuating mechanism mounted on the box bottom wall 5 and including a compound lever having a jointed horizontal actuating arm 10 and a pair of upright actuated arms 11 extending upwardly abreast of journal 1 and terminating in elements 12 arranged to engage the inner face 25 of the collar 13 on the outer end of the journal.

A positioning rod 14 extends longitudinally of the box and is welded at W to the box rear wall 15 and at W' to the box bottom wall 5. A lever mounting housing 16 has supporting feet 17 resting upon the box bottom wall and provided with aligned slots which receive rod 14. The sides of housing 16 journal a fulcrum pin 18 for the lever upright arms 11 and a fulcrum pin 19 for the lever horizontal arm 10.

Pin 18 extends outwardly beyond the sides of housing 16 and journals the rearwardly directed lower terminals 11a of arms 11 so that these arms may pivot on their lower terminals transversely of the box as well as swing with pin 18 longitudinally of the box. Springs 20 yieldingly thrust the upper ends of arms 11 towards the journal but permit the upper ends of these arms to be moved away from each other to accommodate the movement of the mechanism past journal collar 13 when the mechanism is being inserted into the box and removed therefrom.

The actuating arm 10 comprises two sections hinged at 21 with their ends abutting each other at 22 when the sections of the arm are in alignment. The sections may pivot about hinge 21 to the relative position shown in Figure 4 to facilitate the movement of the operating mechanism through the space between the journal and the box bottom and front wall. A lip 23 on the inner or left hand end of lever arm 10 underlies

a lip 24 secured to fulcrum pin 18 and rotating with the upright arms as they swing longitudinally of the box.

The outer or right hand end of lever arm 10 comprises a relatively wide paddle-like member 25 with upstanding sides 26 diverging at their rear ends to guide the arm and the lower end of the pump body as they are moved towards each other into the assembled position shown in Figure 1. The paddle is perforated at 25a to freely pass the lubricant to the pump and this part of the paddle may be screened to bar the entrance of dirt to the pump.

The pump body preferably comprises two chambers 27, 28 with a partition 29 between them, at least one of the chambers having a flexible side wall 30 and preferably the side walls of both chambers are flexible, being formed of leather or a rubber-like composition. Springs 31, 32 tend to expand the pump body to its maximum length but yield to the thrust of the operating lever, during normal functioning of the pump, or to manual pressure when the lubricator is being installed or removed. Preferably spring 32 is stronger than spring 31, whereby chamber 27 will collapse more readily and prior to the collapsing of chamber 28. Flap valves 33 in the pump bottom wall 34 and similar flap valves 35 in partition 29 comprise relatively light metal discs retained by cage-forming staples 36 as set forth in detail in an application filed December 9, 1949, Serial No. 131,975. When lever arm 10 moves downwardly, valves 33 are unseated and oil flows into chamber 27. Upward movement of lever arm 10 causes valves 33 to seat. After chamber 27 is filled with lubricant, upward movement of lever arm 10 causes valves 35 to be unseated and lubricant flows from chamber 27 into chamber 28 and eventually through passage 37 in distributor pad 8 and through the latter along the journal.

Axial reciprocation of the journal crosswise of the box due to loose play provided between these parts will result in the oscillation of lever 10 and the alternate collapsing and expansion of the pump body to feed lubricant to the journal and distributor pad.

Figures 5 and 6 illustrate another form of the invention in which the collapsible pump body 60 comprises lower and upper chambers 60a, 60b, respectively, substantially wider and longer than chambers 27, 28, there being a plurality of coil springs 73 in each chamber tending to expand the chamber and to thrust the operating lever and associated parts to the position shown in Figure 5.

A relatively short positioning rod 61 is welded to the box and the pump lever support 62 is positioned by member 61 and is also welded directly to the box. Member 62 provides bearings 63 for the operating lever which includes a single horizontal arm 64 and transversely spaced upwardly extending arms 65, one at each side of the journal. The operating lever paddle-like perforated arm 64 extends forwardly from support 62 and supports the pump body 60 similarly to the lever horizontal arms 21, 22 previously described.

Pump operating rods 67 are slidably mounted on fixed brackets 68 welded to the box walls and each rod has a terminal 69 at its forward end disposed to engage the inwardly facing shoulder of the journal collar 66 and each rod has its rear end pivoted at 70 to a lever upright arm 65.

Levers 64, 65 are thrust in an anticlockwise

direction by pump chamber springs 73 and by torsion springs 71 anchored to support 62 but are restrained by engagement of contacts 69 with the journal collar 66. When the journal moves to the right, it thrusts lever arms 65 in a clockwise direction, thus elevating arm 64 and collapsing at least the lower pump chamber to effect the discharge of lubricant therefrom through valves 72 in the top wall of the lower chamber. When the journal moves to the left, springs 73 expand the pump chambers and fluid is admitted to the lower chamber through the apertures 74 in lever arm 64 and flap valves 75 in the bottom wall of the chamber.

With this arrangement, the lubricator and pump body is applied after the operating mechanism has been assembled with the box, the distributor supporting springs 76 straddling the operating mechanism.

In both forms of the invention, the entire lubricator is positioned inwardly of the box beyond the end of the journal and the pump operating members engage the inner face of the journal collar which positively actuates the upright arms of the pump lever as the journal moves to the right to collapse the pump body and releases the arms for spring return as the journal moves to the left to permit the pump body to expand.

The details of construction may be varied otherwise than as shown without departing from the spirit of the invention and the exclusive use of those modifications coming within the scope of the claims is contemplated.

What is claimed is:

1. In combination with a railway axle journal having a radial collar at its outer end and a box carried by the journal and including a bottom wall and an upright rear end wall, a journal lubricator comprising a support member mounted on the bottom of the box near the rear end wall thereof, a lever pivoted on said support member with an arm extending forwardly beneath the journal, a lubricant pump carried by said lever arm, means associated with said lever for distributing lubricant from said pump to the journal, and lever actuating means positioned to be engaged by the inner face of the journal collar.

2. In combination with a railway axle journal having a radial collar at its outer end and a box carried by the journal and including a bottom wall and an upright rear end wall, a journal lubricator comprising a support member mounted on the bottom of the box near the rear end wall thereof, a bell crank lever pivoted on said support member with an arm extending forwardly beneath the journal, a lubricant pump carried by said lever arm, means associated with said lever for distributing lubricant from said pump to the journal, said lever having an arm extending upwardly at the side of the journal, and a contact rod slidable longitudinally of the box with one end associated with the upper end of said upwardly extending lever arm and with its other end opposing the inner face of the journal collar.

3. In combination with a railway axle journal having a radial collar at its outer end and a journal box mounted on the journal and including a bottom wall and upstanding side walls, a lever fulcrum supported on said box bottom wall and near the rear of the box a lubricant pump including a bell crank lever pivoted to said fulcrum and having an arm extending substantially horizontally below said journal, and having arms extending upwardly at opposite sides of said

journal, contact elements operatively connected to said upwardly extending arms and slidably mounted upon the side walls of the box and having terminals disposed to engage the inner face of the journal collar, there being yielding means associated with said lever to oppose the thrust of said collar on said contact elements.

4. In combination with a railway axle journal having a radial collar at its outer end and journal box carried thereon, a lubricating device including a collapsible pump positioned beneath the middle portion of the journal, a lever for operating said pump including a horizontal arm extending beneath said pump longitudinally of the journal, there being actuated arms spaced apart transversely of said horizontal arm and extending upwardly at opposite sides of the journal and terminating in elements opposing the inner face of the journal collar.

5. In a railway axle journal lubricator, a lubricant pump, a support member, a pump operating mechanism mounted thereon and including a fulcrum pin extending horizontally transversely of the pump axis, upwardly extending lever arms spaced apart lengthwise of the pin and each having a substantially horizontal lower end extending transversely of and journaled in said fulcrum pin, there being spring means thrusting said arms towards each other about their individual journals.

6. In a railway axle journal lubricator, a lubricant pump, a support member, a pump operating mechanism mounted thereon and including a fulcrum pin extending horizontally transversely of the pump axis, upwardly extending lever arms spaced apart lengthwise of the pin and each having a substantially horizontal lower end extending transversely of and journaled in said fulcrum pin, there being spring means thrusting said arms towards each other about their individual journals, and a pump-carrying horizontally disposed arm operatively connected to said fulcrum pin to turn it and said arms as a unit about the axis of said fulcrum pin.

7. In a railway axle box journal lubricator, a support adapted to be mounted in the journal box, a bell crank lever fulcrumed on said support with arms disposed substantially horizontally and vertically, an element associated with the vertically disposed arm for contact with the vertical inner face of a radial collar of a journal to which the device may be applied, a collapsible pump body associated with the horizontally disposed arm, a distributor pad overlying said pump body for application to the journal, and a member connecting said pad and said pump body, there being passageways with return check valves leading to said pump body and from said pump body to said pad.

8. In a railway axle box journal lubricator, a support adapted to be secured to the journal box, a lever having a fulcrum on said support and having arms extending upwardly from said fulcrum and spaced apart axially of the fulcrum, said lever having an arm disposed substantially horizontally, an element associated with each of said upwardly extending arms for contact with the inner face of a journal collar to which the device may be applied, a collapsible pump body mounted on the horizontally disposed arm, a distributor pad for application to the journal, there being passageways with return check valves leading from the exterior of the pump to said collapsible body and from said collapsible body to said distributor.

9. In a railway axle journal lubricator, a support for application to a journal box, a lever arm fulcrumed on said support and extending substantially horizontally therefrom, a collapsible pump body mounted on the outer end of said lever arm, said arm being made in a plurality of sections arranged end to end and pivoted together with opposing shoulders limiting the pivotal movement of the sections in one direction and accommodating pivotal movement of the sections in the opposite direction.

10. In a railway journal box lubricator, an operating mechanism comprising a support member, an arm pivoted thereto and extending substantially horizontally, another arm pivoted to said support member and extending upwardly, the pivots of said arms being parallel and each of said arms having a lip associated with the lip from the other arm and providing for movement of said horizontal arm by said upwardly extending arm when the upwardly extending arm is moved in one direction, but leaving the upwardly extending arm free to move independently of the horizontal arm when the upwardly extending arm is moved in the opposite direction.

11. In a lubricant distributor for a railway axle journal lubricator, a support member, a bell crank lever fulcrumed thereon and including a horizontal arm and spaced upwardly extending arms, a pump body mounted on said horizontal arm and including a collapsible chamber with inlet and outlet passages having individual return check valves, said upright arms having terminals for opposing and being moved in one direction by the inner face of a radial collar on a journal to which the lubricator is applied, a lubricant distributor for application to the journal to be lubricated, and flexible structure leading from said chamber to said distributor, there being springs associated with said structure and body for thrusting said lever to move said elements in said direction when the device is applied to a journal.

12. In a railway axle journal lubricator, a pump having a substantially cylindrical collapsible body disposed vertically, and an operating mechanism for collapsing said pump body including a substantially horizontally arm with a wide paddle-like terminal arranged to support the pump body, said terminal having upstanding and outwardly diverging sides adapted to receive said pump body between them.

13. In a railway axle box journal lubricator, a support member, a bell crank lever fulcrumed at its angle on said member and having a substantially horizontal arm, a lubricant pump mounted on said horizontal arm, said lever having an upwardly extending arm at one side of the pump, and a journal collar contact rod pivoted to said upwardly extending arm and extending therefrom substantially parallel to said horizontal arm to the opposite side of said pump.

14. In a railway axle box journal lubricator, a support member, a bell crank lever fulcrumed at its angle on said member and having a substantially horizontal arm, a lubricant pump mounted on said horizontal arm, said lever having upwardly extending arms at one side of the pump and spaced apart lengthwise of the lever fulcrum, and journal collar contacting elements connected to the upper ends of said upwardly extending arms and extending therefrom substantially horizontally to the opposite side of said pump.

15. In combination with a railway axle journal

having a collar at its outer end and a box carried on the journal, a journal lubricator comprising a bell crank lever pivotally mounted on the box bottom wall substantially beneath the journal collar and having an arm extending beneath the journal, a pump mounted on said arm, a lubricant distributor applied to the journal and connected to said pump, said lever having an arm extending upwardly alongside of the journal and contacting with the inner face of the journal collar.

16. In combination with a railway axle journal having a collar at its outer end and a box carried on the journal, a journal lubricator comprising a bell crank lever pivotally mounted on the box bottom wall substantially beneath the journal collar and having an arm extending beneath the journal, a pump mounted on said arm, a lubricant distributor applied to the journal and connected to said pump, said lever having a bifurcated arm extending upwardly at opposite sides of the journal with its bifurcations pivoted at their lower end to swing transversely of the journal independently of the first-mentioned arm and to swing longitudinally of the journal with said first-mentioned arm. 25

17. In a railway axle journal lubricator, a support member forming a fulcrum, a bell crank lever fulcrumed on said member and having upwardly extending arm portions spaced apart to receive an axle journal between them, the lever also having an arm extending horizontally from said fulcrum member, a pump mounted on said horizontally extending arm intermediate said upwardly facing arm portions, and elements associated with said upwardly extending arm portions for engaging parts of an axle journal facing lengthwise of the journal at opposite sides of the journal.

JAMES J. HENNESSY.
